UNITED STATES PATENT OFFICE

ALBERT MOREFIELD, OF WAPATO, WASHINGTON

PUMPING MACHINE

Application filed May 7, 1928. Serial No. 275,632.

My invention relates to pumping machines, and it consists in the constructions, arrangements and combinations herein described and claimed.

5 It is an object of my invention to provide a pumping mechanism, wherein a pair of pistons are arranged in tandem relation and connected by a flexible cable, the pistons being held in their spaced relation by a non-com-
10 pressible fluid.

Still further objects of my invention are to provide, first a flexible cable for the rigid rod, now ordinarily used; second, to make possible an automatic replenishing means of the fluid between the pistons; and third, to reduce friction of the moving parts.

Additional objects, advantages and features of invention will be apparent from the following description and accompanying 20 drawings wherein,

Figure 1 is a top plan view of the pump, the pistons having been removed.

Figure 2 is a side elevation thereof,

Figure 3 is a vertical section on the line 25 1—1 of Figure 1, showing the pistons in operative position with the pump barrel.

In carrying out my invention I provide a main barrel 1^a having tandem cylinders 8 between which there is a chamber 5 of slightly 30 greater diameter than the cylinders 8, as clearly shown in Figure 3. The lower end of the barrel 1^a has an intake 9 and foot valve 11 whereby fluid may be retained within the chamber 10. A discharge pipe 15 is suitably 35 connected to the chamber 10, and a check-valve 12 is provided in the pipe 15 to confine fluid therein, as will be hereinafter explained. The upper end of the barrel 1^a has a vent 7 communicating with the upper cylinder 8, 40 whereby air which may be trapped in the cylinder may be vented to the atmosphere.

Intermediate the length of the barrel 1^a and adjacent the upper end of the chamber 5, connection is made between the chamber 5 45 and the discharge pipe 15. A check valve 6 is disposed in this connection so arranged as to permit fluid to enter the chamber 5, at times.

Slidable within the upper and lower cylinders 8 there is a pair of pistons 1 and 2 ar- 50 ranged in tandem relation with one another

and connected by a cable 3. The pistons 1 and 2 are disposed within the cylinders 8 so as to confine the chamber 5 therebetween.

In operation, the chamber 5 is filled with a non-compressible fluid, by removal of the plug 55 13, or the fluid may be supplied to the chamber 5 through the pipe 15 and check valve 6. The pistons 1 and 2 are actuated through the rod 4 from a power plant (not shown). The up or suction stroke of the pistons draws the 60 fluid being pumped, up through the screened inlet 9 into the receiving chamber 10 where it is held by the foot valve 11, which closes automatically upon the start of the down or discharge stroke. The fluid pumped into the 65 chamber 10 is expelled by the piston 2 through the ball-valve 12 by the down or discharge stroke into the discharge pipe 15.

Attention is now directed to Figure 3, wherein it will be seen that power is applied directly to the upper piston 1, by the rod 4 on the down stroke, transmitting motion indirectly to the piston 2 through pressure on the fluid in the chamber 5, so that the flexible cable 3 is kept taut on the down or discharge 75 stroke, as well as on the up or suction stroke. Of course, on the up or suction stroke, the power is applied directly to both the upper piston 1 and the lower piston 2 by reason of the flexible cable 3. 80

To insure a full down or discharging stroke, the chamber 5 is automatically kept constantly filled. Any loss of fluid in the chamber 5, through leakage or otherwise, slackens or permits flexing of the cable 3 on the down or discharge stroke, shortening it and reducing the length of the down stroke in its effective operation on the lower piston 2 and thus reducing the amount of fluid delivered from the pump. However, on the succeeding up or suction stroke of the pistons, the flexible cable 3 is again drawn taut, producing a suction of fluid from the discharge pipe 15 through the ball valve 6 and thus automatically replacing the loss of fluid in the 95 chamber 5.

Removal of the plug 13 gives free access to the ball valve 6, as well as permitting initial charging of the chamber 5 with fluid.

If desired, the pistons 1 and 2 may have 100

leather cups 14 at their ends to afford a packing between the pistons and cylinder walls.

From the foregoing description, it will be readily apparent that engine vibration is not communicated so readily to the pumping mechanism as in the ordinary rod type of pump, and also that there is a considerable reduction of friction and consequent wear. The cushioning effect produced by the fluid medium in the chamber 5 makes possible a more rapid rate of operating speed. Further, the fact that all parts move in a continuous bath of fluid, friction is reduced to a minimum, and increased efficiency in rate of pumping speed is possible.

Claims:

1. A pump of the class described comprising a barrel, a pair of tandem pistons slidably mounted in said barrel, a column of fluid confined therebetween, a flexible cable connecting said pistons, and said barrel having valve means for replenishing fluid between said pistons automatically upon the suction movement of said piston.
2. A pump of the class described comprising a barrel having a fluid chamber, a pair of pistons slidably mounted in said barrel and disposed so as to confine said chamber therebetween, a fluid confined in said chamber, a flexible cable connecting said pistons, a discharge pipe connected to said barrel, and check valve means in said connection whereby to supply fluid from said discharge pipe to said fluid chamber upon upward movement of said pistons.
3. A pump of the class described comprising a barrel having a fluid chamber, a pair of pistons slidably mounted in said barrel and disposed so as to confine said chamber therebetween, a fluid confined in said chamber, a flexible cable connecting said pistons, a discharge pipe connected to said barrel, means for venting air confined between said pistons, and means for supplying fluid from said discharge pipe to said fluid chamber upon upward movement of said pistons.
4. A pump of the class described comprising a barrel having a fluid chamber intermediate its length, an inlet adjacent one end thereof, a foot valve operatively associated therewith, a fluid discharge pipe connected to said barrel above said foot valve, a conduit connecting said discharge pipe and said fluid chamber having a check valve therein permitting passage of fluid in one direction, and a pair of flexibly connected pistons slidably mounted in said barrel and disposed so as to confine a column of fluid adjacent said fluid chamber whereby upon suction stroke of said pistons fluid will be drawn from said discharge pipe into said fluid chamber to replenish the fluid confined between said pistons.

ALBERT MOREFIELD.
